ARNOLD STUCKI, OF PITTSBURGH, PENNSYLVANIA.

FRICITION DRAFT-GEAR.

1,264,222.

Specification of Letters Patent.

Patented Apr. 30, 1918.

Application filed January 20, 1908. Serial No. 411,648.

To all whom it may concern:

Be it known that I, ARNOLD STUCKI, a resident of Pittsburgh, in the county of Allegheny and State of Pennsylvania, have invented a new and useful Improvement in Friction Draft-Gear; and I do hereby declare the following to be a full, clear, and exact description thereof.

This invention relates to the friction draft rigging or gears for railway cars.

The object of the invention is to provide a draft gear of the character specified, which has a graduated yet high resistance and an unfailing release, and which is simple of construction, cheap to manufacture and durable.

The invention comprises the construction and arrangement of parts hereinafter described and claimed.

In the accompanying drawing Figure 1 is in part a plan view and in part a horizontal longitudinal section through the preferred form of my draft gear; Fig. 2 is a longitudinal vertical section of the same; Fig. 3 is a transverse vertical section on the line 3—3 Fig. 2; Fig. 4 is a sectional perspective view of one of the friction wedges; Fig. 5 is a perspective view of one of the partitions or relatively stationary friction plates; and Fig. 6 is a sectional view of the rear portion of the draft gear showing a modification.

In Fig. 1 the draft sills of the car are indicated at 1, and the draft lugs at 2. 3 indicates the usual front follower plate, and 4 indicates the rear follower plate, which latter, however, is of special construction. The coupler strap or yoke is shown at 5 and passes over the draft gear at top and bottom and around a suitable saddle 6, bearing against the rear follower plate 4, as is common in railway draft mechanism.

The draft gear comprises the follower plates or followers above named, and the housing or barrel 8, and the friction and spring mechanism contained in said housing. The housing preferably is of a rectangular shape in cross-section, as shown. It is strengthened at top, bottom and sides by ribs or flanges 9. In its preferred form it is open at the rear end as shown in Figs. 1 and 2, said rear end having an interlocking or lost motion connection with a rear follower plate 4, so as to permit a limited relative longitudinal movement of these parts

for a purpose hereinafter described. The drawings show a special form of connection formed by a flange 10 on the rear end of the housing, which flange at two or more points is interrupted or cut away as at 30 to permit the passage of hooks 11 formed on or secured to the follower plates. The plate and housing are assembled by passing the hooks through the interrupted spaces in the flange 10, and then giving the parts a partial turn with reference to each other, thus locking them together. The hooks 11 are of sufficient length to allow a limited relative longitudinal movement between the housing and the rear follower plate.

The forward end of the housing is flared so as to provide inclined or angular friction surfaces 12. In the housing and preferably extending parallel to the faces 12 are angular partition plates or relatively stationary friction plates 14, which are mounted in a manner to permit them to move laterally with reference to the axis of the draft gear but having no movement longitudinally of the housing; or in other words, so that they move longitudinally with the housing but have freedom of movement toward and from the axis of the housing. This connection may be made in various ways. As shown in the drawings, the partition or friction plates 14 are provided on their top and bottom edges with lugs or bosses 15 which project into openings 16 in the top and bottom walls of the housing. The openings 16 are in the form of slots in order that the plates 14 with their integral lugs can be gotten in and out. The bosses or lugs 15 are formed of large size as shown, to give ample strength and prevent crushing of the metal under the severe stresses to which the draft gear is subjected.

The stationary friction plates or partitions 14 have inner and outer friction surfaces preferably but not necessarily parallel to each other, as shown. Between each of these partitions or plates 14 and the friction surfaces 12 of the housing are movable friction plates 17, each of which has friction faces contacting on the outside with the friction surfaces 12 of the housing, and on the inside with the partitions or plates 14. These surfaces are preferably parallel or at least on a very slight angle, less than the angle of friction. The plates 17 move in straight

lines and do not cause lateral movement in any other part of the mechanism, and their resisting effect is due entirely to the amount of friction generated on the two rubbing faces thereof.

Bearing against the inner faces of the stationary friction plates or partitions 14 are the angular friction members or wedges 18. These wedges are spread or caused to exert a pressure against the partitions 14 by means of a suitable spreader spring which preferably is a double elliptical spring 19 having graduated leaves so as to give great flexibility. This spring has a graduated or increasing resistance as it becomes compressed and forms with the friction member 18 a spreader element which acts also as a friction element on account of the motion of its rubbing face relative to the element 14, which is longitudinally stationary relative to the housing 8. The spring 19 preferably is without bands to economize space, the leaves being held against relative displacement by coöoperating bosses and sockets formed in said leaves. The spring as an entirety is held against displacement by reason of being seated between flanges 20 on the top and bottom edges of the wedges. These flanges also serve to strengthen the wedges so the latter may be made of minimum weight commensurate with the desired strength and stiffness. The forward or outer ends of the wedges are provided with flanges 21 of ample strength to withstand the battering of the front follower plate.

To the rear of the friction elements described is a transverse plate or washer 22, and interposed between this and the rear follower plate 4 is a strong helical spring 23 which serves the two-fold purpose of giving the preliminary resistance to the shortening of the draft gear and as a release spring for the gear. The drawings show the wedges 18 as of greater length than the parallel friction plates 17, so that normally the front follower plate contacts with the wedges and moves the same before acting on the parallel friction plates. This is for the purpose of securing the action of the angular and the parallel friction elements in succession and giving a graduated or increasing resistance to the shortening of the gear. When fully compressed the plate or washer 22 contacts only with the wedges, the shorter friction plates not reaching said transverse plate 22. While I have described and shown a draft gear in which the angularly movable friction element is first brought into action, and then the parallel element, or element movable parallel to its opposite parallel faces, I regard the employment of separate frictional elements independently movable and each having a rubbing face frictionally contacting with an independent rubbing surface, as broadly within the spirit

of my invention when arranged with means for moving said elements successively along their mating surfaces to give a graduated and increasing frictional resistance.

Fig. 6 shows a modification in which the rear end of the housing is closed by the wall 4* which takes the place of the rear follower plate. With this modification, the rear wall acts as an abutment for the release spring 23, and also serves the function of a follower plate, but the spring 23 in such case acts merely as a release spring and not to give the preliminary resistance as in the preferred modification.

The drawing shows the gear in its expanded position; that is, when not subjected to either buffing or draft stress. When subjected to either of these stresses, the gear shortens in the usual way and brings its several elements into action. The friction between the wedges and the angular friction plates 14 is due to the pressure of the spreader spring, and the angle of these members is such that the resistance on the angular surfaces is greater than the initial strength of the spring 23. Consequently, the first movement in the shortening of the gear is a longitudinal one between the housing and the rear follower plate, this movement compressing the spring 23. The latter, therefore, acts as a preliminary resistance, and as it yields quite readily the gear is flexible to take up slight shocks. In the further shortening of the gear, the front follower plate 3 acts on the outer ends of the wedges 18, forcing the same inwardly between the partitions or friction plates 14. This movement causes the wedges to contract or move toward the center, placing the spreader spring under increased compression and materially augmenting its initial pressure, tending to force the wedges outwardly. The resistance to the inward movement of the wedges is therefore an increasing one as the gear continues to shorten. When the gear has shortened sufficiently to bring the front follower plate into contact with the ends of the friction plates 17 the latter are also moved inwardly in straight lines and add the friction on their opposite parallel faces to the resistance due to the increasing shortening of the spring 23 and the increasing resistance due to the inward movement of the wedges. The amount of friction created by the movement of the parallel plates 17 is dependent upon the outward thrust or pressure of the partitions 14, due to the spreading action of the spring 19 and as the latter is very powerful, especially when the wedges have moved inwardly a considerable distance, a very large frictional resistance is added to the gear by the movement of the plates 17.

The gear described, therefore, brings successively into action three separate resisting

- functions, namely, first, the preliminary resistance of the spring 23 due to the lost motion connection between the housing and the rear follower plate; second, the resistance due to the inward movement of the angular friction members or wedges 18 acting on the relatively stationary friction plates or partitions 14, this resistance being due to both friction and angularity; and 10 third, the resistance due to the movements of the friction plates 17. The resistance, therefore, of the gear is a graduated one, being comparatively easy or small at the beginning of the shortening so as to effectively absorb the slight shocks incident to the operation of trains, and gradually increasing and becoming exceedingly heavy so as to effectively take care of heavy shocks. The spring 23 of course gradually increases 20 in its resistance as it shortens.
- When the gear is fully compressed or closed the transverse plate or washer 22 is contacted only by the inner ends of the wedges 18 due to the fact that these are 25 longer than the parallel friction plates 17. Consequently, when the gear is relieved of the buffing or draft stresses, the entire strength of the spring 23, which is very large on account of its compressed condition, is exerted against the wedges alone, and as the friction faces of the latter are on an angle said spring will not fail to force the wedges outwardly and insure a release 30 of the friction gear. After the wedges are once started, the friction co-efficient drops to one half, and when the plate 22 strikes 17 it easily overcomes their resistance, especially since the lateral pressure is already reduced.
- 40 The preferred gear utilizes three elements of resistance, each one being based on a different and distinct principle. One is dependent on a coil spring for its resistance. Another, called a "parallel friction element", 45 is based on friction alone, this element having two bearing surfaces which are practically parallel, so that the mating friction surfaces on each side do not close or depart from each other while this element moves.
- 50 Each plate 17 forms such a parallel friction element. The surfaces could be made slightly convergent without affecting the operation materially, as long as the angle is kept small to exclude the possibility of the lateral pressure causing longitudinal motion, which would destroy the possibility of succession in the starting. The third or "angular friction element" uses friction and angularity in 55 obtaining its resistance, and consists of a wedge member, which in closing not only creates friction between itself and the inclined mating surface, but also obtains much resistance from its inward movement. The greater the angle, the greater the resistance.
- 60 By my invention the two independently movable frictional elements, that is, the element with parallel faces, and the spreader element or wedge, are independently movable in a well defined course not dependent on play or slack in the gear. This is to be 70 distinguished from such draft gear constructions as that shown, for instance in United States Letters Patent No. 391,997, to Westinghouse, in which patent the only frictional movement which takes up any substantial 75 part of the operative stresses is that of the parallel friction plates. By the term "operative stresses" as used in a number of the accompanying claims, I mean to include draft or buffing stresses operative on the draft 80 gear in the usual manner well understood in the art.
- What I claim is:
1. A friction draft gear having a friction element provided with substantially parallel 85 opposite friction faces set at an angle to the draft axis, a spreader device including a friction face set at substantially the same angle as said faces, and means for moving both of said friction elements parallel to their friction faces.
  2. A friction draft gear having a friction element provided with two substantially parallel friction faces set at an angle to the draft axis, another element laterally movable relative to the draft axis and provided with a friction face, another element having friction surfaces mating with each of said friction faces, a spreader spring opposing the motion of said other element laterally 95 of the draft axis, and means for moving said elements parallel to their friction faces.
  3. In a friction draft gear the combination of two independently movable friction elements provided with friction faces, a partition plate between said elements and provided with opposite frictional surfaces mating with the faces of each of said elements, and means for first moving one of said friction elements to provide a frictional resistance, and then moving the other of said friction elements to increase said frictional resistance.
  4. A friction draft gear having a friction element provided with substantially parallel 105 opposite friction faces, a spreader element having a friction face set at an angle to the draft axis, and a follower normally in contact with one of said elements and out of contact with the other, and arranged on a 110 shortening of the gear to successively move said spreader element and then the friction element parallel to their respective friction faces.
  5. A friction draft gear having a movable 125 friction element provided with opposite parallel friction faces set at an angle to the draft axis, another friction element provided with a friction face at an angle to the axis, friction surfaces in contact with said 130

faces, means for opposing a yielding resistance to the motion of said other element laterally of the draft axis, and a follower normally in contact with said other element and arranged to first move said element against said resistance parallel to its friction face and then move said first mentioned element parallel to its friction faces.

6. A friction draft gear having a housing, 10 front and rear follower plates, and a lost motion connection between one of said follower plates and said housing, successively movable friction elements in said housing, and a spring between said follower plate 15 and said elements and arranged to act on said elements successively to return the same to normal position.

7. A friction draft gear comprising a housing having friction surfaces, follower 20 plates, friction wedges in the housing, a spreader spring therefor, angularly arranged friction plates coöperating with said wedges and arranged to move transversely of the housing but having no movement longitudinally thereof, and a friction plate 25 movable on a shortening of the gear and contacting frictionally with the friction face on said housing and said angular friction plate.

8. A friction draft gear comprising a housing having friction surfaces, angular friction wedges, a spreader spring therefor, angularly arranged friction plates contacting with said wedges and arranged to move 30 transversely of the gear but not longitudinally thereof, movable friction plates interposed between said angular friction plates and the friction surfaces of the housing, and a follower plate arranged to contact with 35

said wedges and said movable friction plates 40 successively.

9. A friction draft gear comprising a housing, follower plates, angular friction wedges in the housing, a spreader spring therefor, angularly arranged friction plates 45 contacting with said wedges and arranged to have movement transversely but not longitudinally of the gear, movable friction plates interposed between the housing and said angularly arranged friction plates, and 50 a spring interposed between the inner ends of said wedges and movable friction plates and the rear follower plate.

10. A friction draft gear comprising a housing, angular friction wedges, a spreader 55 spring therefor, angularly arranged friction plates contacting with said wedges and arranged to move transversely but not longitudinally of the housing, friction plates having parallel faces interposed between said 60 angular friction plates and the housing and contacting therewith, said parallel friction plates and wedges being of different lengths so as to be operated in succession, a front follower plate arranged to contact with said 65 wedges and parallel friction plates, a transverse plate at the inner ends of said wedges and parallel friction plates, a rear follower plate, and a spring interposed between said follower plate and the transverse plate at 70 the rear ends of the wedges and parallel friction plates.

In testimony whereof, I the said ARNOLD STUCKI have hereunto set my hand.
